[57] CLAIM

The ornamental design for a shoulder support for cameras or similar articles, as shown.

DESCRIPTION

FIG. 1 is a top and left front perspective view of a shoulder support for cameras or similar articles showing my new design;

FIG. 2 is a left side elevational view thereof;

FIG. 3 is a top plan view thereof;

FIG. 4 is a right side elevational view thereof;

FIG. 5 is a bottom plan view thereof;

FIG. 6 is a rear elevational view thereof; and

FIG. 7 is a front elevational view thereof.
